UNITED STATES PATENT OFFICE.

IGNAZ KREIDL, OF VIENNA, AUSTRIA-HUNGARY.

PROCESS OF PRODUCING AN OPAQUING AGENT FOR WHITE ENAMEL.

Specification of Reissued Letters Patent. Reissued Aug. 25, 1914.

13,791.

No Drawing. Original No. 1,024,495, dated April 23, 1912. Serial No. 630,157. Application for reissue filed October 29, 1912. Serial No. 728,509.

To all whom it may concern:

Be it known that I, IGNAZ KREIDL, a subject of the Emperor of Austria-Hungary, residing at XXI Kohlgasse 5-9, Vienna, in the Empire of Austria-Hungary, have invented a new and useful Improved Process of Producing an Opaquing Agent for White Enamel, of which the following is a specification.

10 My invention relates to an improved method for manufacturing a clouding or opaquing agent for white enamels.

It has already been proposed to use the chemically pure oxid of zirconium in connection with the manufacture of white enamels for rendering the same turbid or opaque. It has, however, been found that the covering power of the oxid of zirconium which is to form a substitute for the oxid 20 of tin heretofore employed is relatively speaking very small and that in order to obtain the same turbid or cloudy effects which are obtainable with oxid of tin, it is necessary to use much greater quantities of oxid 25 of zirconium than of oxid of tin. For this reason the substitution of oxid of zirconium for oxid of tin is too expensive to be adopted in actual practice. Further it has been proposed to employ natural or normal silicate of zirconium as clouding agent. Experiments carried out in this direction, however, have revealed that natural or normal silicate of zirconium only possesses a very 30 weak clouding or thickening action, that is to say, it is only capable of rendering the enamel turbid or opaque to a very slight extent. It was therefore heretofore assumed that the silicates of zirconium could not be used at all as clouding agents.

40 This invention is based on the recognition of the fact that from the natural or from a normal silicate of zirconium by separation only of a portion of the silicic acid a voluminous product is obtained, which possesses an extremely great covering power. 45 This voluminous product the manufacture of which is considerably cheaper than the manufacture of the chemically pure oxid possesses a considerably greater covering 50 power than oxid of zirconium.

It has been found that the voluminous product produced according to the invention, and if used in the same quantity as the oxid of tin, produces practically double

the covering effect obtained with the latter. 55 When used in the same quantity as the oxid of zirconium the voluminous product according to the invention contains less of the valuable zirconium than there is contained in the same quantity of zirconium oxid. 60 From this it follows that the employment of the voluminous products according to the invention would be more economical even if the same were only to produce the same 65 covering effect as produced by the oxid of zirconium.

The following method is, for instance, suitable for producing such voluminous products. The normal or natural silicates of zirconium are first of all finely powdered 70 and freed from coloring admixtures by treating this powder with acids such as hydrochloric acid or the like. Thereafter these silicates are heated with an alkaline agent, such as carbonates or hydrates of the alkalis 75 (preferably the carbonate or hydrate of sodium) or the like under such conditions that only a partial separating out of the silicic acid takes place. Experience has taught that the complete separating out of the silicic acid, or the complete conversion into carbonate, hydrate, or oxy-alkaline compound, is produced by melting or heating the silicate at very high temperatures with a great 80 surplus of an alkaline agent. This result 85 may be prevented either by using smaller quantities of such agents, or lower temperatures. A mass suitable for the purposes of this invention may for example be obtained if four times the quantity by weight of caustic soda is used for the process and a working temperature of 500 to 600° C. employed. When heating the mixture only a portion of the silicic acid will separate out and the 90 whole structure will be loosened. The mass 95 is then treated with water and weak acid so as to remove the alkaline matter, such as alkalis or alkaline earths and alkaline silicates, by which means a separating out of the silicic acid is avoided. After having removed the solution the mass is dried and (when necessary) glazed, or heated to incandescence; there then remains a voluminous product. This voluminous product may 100 also be obtained by synthesis.

What I claim as my invention and desire to secure by Letters Patent is:—

1. The process of producing a clouding

or opaquing agent for white enamel consisting in freeing powdered silicate of zirconium from coloring matter by treatment with acid, then mixing it with four times the weight of caustic alkali, heating to a temperature of from 500 to 600 degrees centigrade, treating with a fluid to remove the alkali, drying and glowing.

2. The process of producing a clouding or opaquing agent for white enamel, consisting in freeing powdered silicate of zirconium from coloring matter by treatment with acid, then mixing it with caustic alkali, heating to between 500 and 600 degrees centigrade, washing out the alkali, drying and glowing.

3. The process of producing a clouding or opaquing agent for white enamel consisting in freeing powdered silicate of zirconium from coloring matter by treatment with acid, then mixing it with four times the weight of caustic soda, heating to between 500 and 600 degrees centigrade, washing out the alkali, drying and glowing.

25 4. The process of producing a clouding or opaquing agent for white enamel consisting in partially removing the silicic acid from silicate of zirconium by means of an alkaline agent and treating the mass to remove alkaline matter.

5. The process of producing a clouding or opaquing agent for white enamel, consisting in heating silicate of zirconium with an alkaline agent to partially remove the silicic acid, then removing alkaline matter, and

drying the mass to produce a voluminous product.

6. The process of producing a clouding or opaquing agent for white enamel, consisting in treating zirconium silicate with an alkaline agent to partially remove the silicic acid, and removing the combined alkali therefrom.

7. The process of producing a clouding or opaquing agent for white enamel, consisting in partially removing the silicic acid from silicate of zirconium by means of an alkaline agent, then washing, removing alkaline matter, and drying or heating the mass to produce a voluminous product.

8. The process of producing a clouding or opaquing agent for white enamel consisting in partially removing the silicic acid from a natural silicate of zirconium by means of an alkaline agent and treating the mass to remove alkaline matter contained in the mass.

9. The described clouding or opaquing agent for white enamel, being a voluminous product consisting of a natural silicate of zirconium from which a portion of silicic acid has been removed.

In witness whereof I have hereunto signed my name in the presence of two subscribing witnesses.

Dr. IGNAZ KREIDL.
